(57) **CLAIM**

The ornamental design for a chair as shown and described herein.

DESCRIPTION

FIG. 1 is a front perspective of the chair.

FIG. 2 is a rear perspective of the chair of FIG. 1.

FIG. 3 is a front elevational view of the chair of FIG. 1.

FIG. 4 is a rear elevational view of the chair of FIG. 1.

FIG. 5 is a side elevational view of the chair of FIG. 1, which is a mirror image of the opposing side thereof.

FIG. 6 is a top plan view of the chair of FIG. 1; and,
FIG. 7 is a bottom view of the chair of FIG. 1.

The broken lines and gray shading within the broken lines, shown in the drawings illustrate portions of the article that form no part of the claimed design. Any shading in the drawings is for the purpose of depicting contours of the article. No color is claimed.
